BUFFING WHEEL

George R. Churchill, Hingham, Mass.

Application April 29, 1948, Serial No. 24,059

6 Claims. (Cl. 51—193)

1

This invention relates to a buffing wheel.

The object of the invention is to provide a novel and improved construction of buffing wheel made up of a number of sections and having provision for air-cooling the component sections of the buffing wheel in a novel, superior and economical manner.

A further object of the invention is to provide a novel spacing disc for use between adjacent sections of a sectional buffing wheel which has provision for enabling the air to be conducted there through from one portion of the surface of the buffing wheel to another by the suction developed when the work is held up against the face of the wheel thus effectively cooling the adjacent sections of the wheel.

With these objects in view and such others as may hereinafter appear, the invention consists in the buffing wheel and in the spacing and air-cooling disc for use in a buffing wheel, all as hereinafter described and particularly defined in the claims at the end of this specification.

In the drawings illustrating the preferred embodiment of the invention, Fig. 1 is a side elevation of the present buffing wheel; Fig. 2 is a vertical, cross-sectional view of the present buffing wheel illustrating in section the spacing members between adjacent wheel sections of the buffing wheel; Fig. 3 is an end elevation of one of the preferred spacing and air-cooling discs and Fig. 4 is a detail to be referred to.

Prior to the present invention various attempts have been made to air-cool buffing wheels of the multi-section type and such attempts have been confined to the conduction of air axially through a hollow supporting shaft or arbor and the distribution of the air outwardly between adjacent sections. This required specially constructed arbors and special spacing members between the sections.

I have discovered that a multi-section buffing wheel may be successfully air-cooled by the use of specially designed spacing members, disposed between adjacent sections of the wheel without any special arbor. The spacing members are constructed to permit the passage of air from one portion of the surface of the buffing wheel through the spacing members and to permit the air to thereafter emerge at a different portion of the buffing wheel surface. The air movement is actuated by the vacuum set up when the work is held against one portion of the face of the wheel. It is my belief that when the work is held against the front face of the wheel, an area of low pressure is set up in such a location

2

by reason of the rapidity by which the wheel is rotated and the distortion by the work of the rapidly revolving body of air in contact with the surface of the wheel, thus producing an area or region of low pressure at the front of the wheel. The provision of the especially constructed spacing members between adjacent sections of the buffing wheel makes it possible to utilize this region of low pressure to effect air movement through and between adjacent sections from one portion of the face of the buffing wheel to the second portion of the face of the buffing wheel in the vicinity of the region of low pressure, with the result that a definite flow of cool air is caused to take place between adjacent sections thus effecting efficient air-cooling of the wheel.

Referring now to the drawings, the multi-section buffing wheel shown in Figures 1 and 2 is made up of a plurality of sections 10, mounted upon a supporting spindle or hub 12 and clamped under pressure between end plates 14 by a nut threaded onto the threaded portion of the end of the spindle. One of the end plates 14 abuts an end of the rotary element upon which the spindle is mounted. The wheel is further provided with a plurality of spacing members 20 of novel construction which are mounted upon the spindle or hub 12, one between each pair of adjacent buffing wheel sections. The spacing members are constructed to provide an air conduit through which the air may flow from one or more portions of the periphery of the wheel to emerge between adjacent sections at the front of the wheel, the movement of the air being induced by the region of low pressure set up at the front of the wheel when work is held against the face of the wheel during the normal commercial use of the wheel.

40 The spacing members 20 are preferably provided with portions which effectively space apart adjacent sections of the wheel to permit such air movement and as herein shown each facing member preferably takes the form illustrated in Figures 1, 2, and 3. As therein shown, each spacing member is provided with a rim portion 22 engaging the side of the buffing wheel section and spacing the same from the next adjacent section. These spacing members 20 are provided with a central hole adapted to snugly fit upon the central spindle 12 on which the buffing wheel sections are mounted.

In the preferred embodiment of the invention, the individual buffing wheel sections 10 are preferably made in accordance with my U. S. Letters

Patent No. 2,146,284 issued February 7, 1939. As set forth in said patent, each section comprises a plurality of individual cloth buffing elements 11 arranged to extend radially and the inner and lower ends of which are secured in ring formation by weaving wires 42 extending around and between successive buffing elements. The ring of buffing wheel elements thus formed is stapled or otherwise secured to a central hub or supporting plate 26, preferably of sheet metal and to which the individual members may be secured by staples 27, as shown. The illustrated spacing member 20 is particularly designed for use with a buffing wheel section of the type described and which is illustrated in my patent as aforesaid. As illustrated in the drawings, the ring section of the buffing wheel spacing member is provided with an annular shoulder or offset portion 29 disposed to fit snugly under the inner ends of the radially extended buffing wheel elements 11 and the central portion of the spacing plate or disc 20 is dished into the shape illustrated in Figs. 2 and 3 so as to provide and form an air chamber 31 between one face of the disc and the adjacent metal plate 26. The spacing member 20 is further provided with a series of circumferentially-spaced slots or openings 34 which are formed in the shoulder and rimmed portions 29, 22 of the spacing discs, as illustrated in Figures 1 and 2 thus affording a direct air passage into the chamber 31 formed between the concave face of the spacing disc and the metal plate 26 of the particular wheel section. The thickness or depth of the spacing members is related to the size or depth of the ends of the buffing elements constituting the section of the buffing wheel so as to provide at all times a space under the spacing members through which air may flow radially outwardly during the operation of the wheel under the influence of the region of low pressure above referred to, thus providing a continuous air passage from one portion of the face of the wheel through the space between adjacent sections and around the individual buffing elements thereof, the ports provided in the rimmed and shouldered portions of the spacing member affording outlets and inlets through which the air may pass as described. The staples 27 above referred to, by which the individual buffing elements are secured to the plates 26 in practice project a small distance beyond the face of each side of the buffing wheel section so that when engaged by the rim portion of the spacing member, ample air space is insured between both surfaces of the rim section of the spacing member so that effective distribution of the air is accomplished irrespective of the amount of pressure with which the wheel sections are clamped together.

In Fig. 4, I have illustrated a vertical sectional view of adjacent sections of a different type of buffing wheel, with which the present spacing members 20 may be used with advantage. As shown each section is made of a plurality of full discs of cloth mounted upon the spindle 12 and a spacing ring 40 of cloth, cardboard or other suitable material may be sewn or otherwise secured to one face of the section against which the rim portion 22 of the present spacing member 20 may engage in order to provide the desired air chamber 31 beneath the body portion of the spacing disc.

While the preferred embodiments of the invention have been herein illustrated and described, it will be understood that the invention may be

embodied in other forms within the scope of the following claims.

Having thus described the invention, what is claimed is:

- 5 1. A multi-section buffing wheel comprising a plurality of buffing wheel sections, a spindle on which said sections are mounted and a plurality of spacing members between adjacent sections, each of said buffing wheel sections including a flat circular plate mounted on the spindle and a ring of radially-extended buffing elements secured at their inner ends to one side of said plate and terminating a substantial distance from said spindle, said spacing members being provided with rim portions engaging the opposite lateral face of the inner end portions of said radially extended buffing elements and provided with a central portion disposed within the circular opening formed by said ring of buffing elements and shaped to form an air chamber between one face of the spacing member and the supporting plate of an adjacent buffing wheel section, said spacing members being also provided with air ports for conducting air into and from the air chamber at the rim section of said spacing members.
- 10 2. A buffing wheel as defined in claim 1 wherein the spacing members are provided with an offset portion disposed to fit under the inner ends of said buffing elements and wherein the ports are formed in the rim and offset portions of the spacing members.
- 15 3. A multi-section buffing wheel having a plurality of sections and means for operatively supporting the sections upon a spindle, said sections comprising annular buffing rings and said supporting means comprising flat centering disks, one secured to each ring along one lateral face adjacent the inner diameter of said buffing rings and through which the spindle is arranged to pass to center and support the buffing rings thereon, a plurality of detached spacing disks mounted upon the spindle with one disk between adjacent ring sections, each of said disks having offset rim portions arranged to engage the opposite lateral face of said rings and having portions disposed within the central opening formed within the annular buffing rings and being shaped to form a substantial air chamber disposed between the face of said spacing disk remote from the centering disk and the next adjacent buffing section, said spacing disks having air ports formed in the rim portion thereof and communicating with said air chamber to permit passage of air from one portion of the peripheral face of the buffing wheel to another portion thereof.
- 20 4. A multi-section buffing wheel having a plurality of annular ring sections, each section having a flat circular plate secured to a lateral face adjacent the inner diameter of a section for supporting the sections upon and spaced from a spindle, means separate from said supporting means for spacing adjacent sections from one another comprising a spacing disk having a rim portion engaging the opposite lateral face adjacent the inner diameter of said ring sections and shaped to provide a substantial air chamber between a face of the spacing disk remote from said supporting plate and the adjacent buffing wheel section and being provided at the rim portion thereof with a plurality of circumferentially spaced openings constituting air ports, said air ports communicating with the air chamber whereby when the work is held against the face 25 of the wheel, movement of air is induced from

one portion of the wheel into said air chamber to emerge through said ports at another portion of the face of said wheel to effect cooling of the wheel.

5. A multi-section buffing wheel as defined in claim 4 wherein the supporting plates and the ring sections are provided with securing means having portions which extend between the plates and said rim portions providing additional space to insure the free passage of air between the sections and around the hub portions of the spacing members when the sections are clamped together on the spindle.

6. A multi-section buffing wheel comprising a plurality of sections mounted upon a spindle, and a plurality of spacing disks, one between each pair of adjacent sections, said spacing disks having offset rim portions provided with air ports and engaging a lateral face of a section, the inner portions of the disks being shaped to provide an air chamber of substantial size between one face of each disk and an adjacent section communicating with said ports to permit the conduction of air from the peripheral face of the wheel,

around the inner portion of the spacing disks and thence outwardly to a second portion of the peripheral face of the wheel by air movement induced by the region of low pressure set up when the work is held against the face of the wheel, and a spacing ring disposed between the rim portion of each disk and the opposite lateral face of an adjacent section to insure the free passage of air between the sections and around the inner portions of the spacing disks when the sections are clamped together on the spindle.

GEORGE R. CHURCHILL.
